REFRIGERATOR WINDOW

Robert M. Robinson, Philadelphia, Pa., assignor
of one-half to Noar Klein, Philadelphia, Pa.

Application March 8, 1940, Serial No. 322,901

12 Claims. (Cl. 62—89.5)

This invention relates to refrigerator windows, and particularly to means to prevent condensation of moisture on the surfaces of the panes comprising such windows.

5 Owing to changes of volume of air entrapped between spaced panes in windows of refrigerator show cases and the like, incident to variations of temperatures imposed upon the windows, both inside and outside of the case, leakage about the
10 edges of the panes is inevitable, so that even if the initial charge of entrapped air is dehydrated, an eventual "pumping" action replaces this with moisture-laden atmosphere, and eventually the moisture content is such as to cause condensation
15 on the cold window panes. Many efforts have been made in the past to cure this tendency, as by providing a reservoir of dehydrating material to absorb the moisture, either by direct contact with the spaces between the panes, or by forming
20 a mechanically actuated closed circuit through the space between the panes and a deliquescent agent, or the like. These expedients are expensive to build and to service and are of relatively short life. The advent of the low temperature case adapted to preserve frozen foods, has complicated the situation and exposed the inadequacies of present condensation preventing methods.

It is among the objects of this invention: to improve the window construction of show cases and the like; to utilize the natural periodic cyclic variation of temperatures of the refrigerator for maintaining the windows free from condensed moisture; to adapt the natural laws affecting the phenomena of relative humidity, convection of air currents, and air circulation to prevent condensation of moisture on the panes of the window; to provide a substantially closed circulating system for the spaces between panes of a window; to provide with a circulating system for air between spaced window panes means for extracting moisture therefrom; to eliminate or sharply minimize the chances of deposit of dust, films, spoor or mold on the inner surfaces of spaced window panes in a refrigerator or show case; to provide a dehydrating system for windows which is susceptible to quick, easy and cheap replacement or recharging; to provide a circulation through the spaces between a plurality of panes such circulation passing through an aperture in the glass; to reduce the cost of condensation free windows; to provide a closed circulation system for window spaces containing a condenser for entrapped moisture; to provide a novel heating means for accelerating an air circulation; to provide means for utilizing otherwise waste heat of

a condenser for air circulating purposes; and many other objects and advantages will become more apparent as the description proceeds.

In the accompanying drawing:

Fig. 1 represents a fragmentary vertical section through a window and through the associated moisture condenser element, showing the circulating stream by arrows;

Fig. 2 represents a diagrammatic perspective of the several spaced panes and the channels and conduits associated therewith showing the circulation by arrows;

Fig. 3 represents a vertical section through the moisture condensing unit for the window.

In carrying out the invention in a preferred form a metallic moisture condensing device is arranged to be chilled by the internal temperatures in the box containing the window, and communicates at the bottom through the innermost pane of the window, and channels are provided through the other panes to an upper outlet passage leading into the top of the condenser. The natural thermal circulation thus secured travelling downward through the moisture condenser, laterally and longitudinally in series flow through the several spaces between panes and return into the top of the condenser will be augmented, if necessary, by a relatively small heating unit in the front space of the window, having the dual function of gently warming the glass to prevent external condensation thereon, and also imparting energy to the closed circulation.

The details of the refrigerator proper or other window containing device will naturally vary according to demands, but may be generally set out as comprising a front wall 10, the window 11, to be described, sealed at the top, bottom and sides as far as practicable, as is common with windows of this type, and at the top merges into the sloping or slanting insulating front wall 20, connected by insulating top wall 21, to insulating rear wall 22. The refrigerator compartment or cabinet space 23, is completed by suitable end insulating walls 24 and lower insulating floor or sub-floor 25.

The "sight" window through which the contents of the case are observed, and which it is important to keep clean, dry and dustless at all times, may comprise a single space between two spaced generally parallel panes, or any additional number of dry air spaces desired. Preferably and desirably, especially in view of the insulation demands incident to the low temperatures maintained, the window comprises four parallel spaced panes respectively, 12, 14, 16 and 18, in order outwardly from the interior of the case. Panes 12 and 14 define a rear or inner up-

ward flowing space 13. Intermediate air space 15 between panes 14 and 16 comprises a generally downward flow of circulating air stream entering the said space through upper transverse bore 35 5 of pane 14. Front upward flow space 17 is defined by pane 16 and front pane 18 and has an entrance for circulating air through a low transverse bore 36 of glass 16.

With the type of box particularly benefitted 10 by this invention a suitable powerful freezing unit (not shown except for a fragment of the hotter end of the condensing coil thereof, at 26) is disposed below the sub-floor 25, but connected to suitable coils 27 by which the temperature of 15 the compartment can be maintained at a satisfactory degree. Illustratively only the preferred temperature is between 0° F. and -15° F. Suitable shelving and the like will be provided as may be deemed necessary.

20 Preferably disposed at one side of the window so as not to obtrude upon nor obstruct the sight through the window, is the preferably substantially vertical cylindrical metallic condenser 28. This may be of various shapes, and extend either 25 in whole or in part horizontally as well as vertically, if desired, and may have such external or internal finning and the like (not shown) as may be found desirable. The lower end of the dehydrating tube or condenser 28 is suitably 30 threaded or otherwise provided so as removably to receive and tightly join, a closure cap or moisture trap or retainer 30, which may comprise a mere receptacle, or be a container of a dehydrating element such as calcium chloride, silica gel, 35 or the like. At a slight distance above the upper end of the closure cap 30, an intake or inlet tube 31 extends generally radially of the cylinder 28, or parallel to a radius, through a bent connection, to sealed entrance through a small bore or aperture 32 formed in the inner pane of glass 12 40 toward its lower end and near one horizontal end thereof. The upper end of the condenser cylinder 28 communicates with a suitably disposed and bent conduit 33 partially within the chamber 23, and partially within the insulation 45 of the front wall 20, and the latter preferably extends within the upper frame of the window the full length of the window in space 17 to communication through an exhaust port 34 with said 50 front space 17 at the far end, horizontally, away from the intake 31, and vertically spaced from same also, as it is disposed at the top of the window.

To facilitate and direct flow between the several panes in series, as previously noted, the rear complementary pane 14 is drilled at 35 in close proximity to the upper edge to form a passage between the spaces 13 and 15, this passage 35 entering the space 13 at the opposite end from 60 the bore 32 in the pane 12. The transverse duct or bore 36 in pane 16 establishing communication between spaces 15 and 17 is generally laterally aligned with the bore 32 in pane 12.

It will be clear that window 12 is always the 65 coldest, and that progressing toward the front the respective panes will become gradually warmer, until the very front pane 18 will be somewhat less than that of the atmosphere surrounding the case. It will also be clear that with the 70 cylinder 28 made of thin metal such as of copper or metal of like conductivity, it will be chilled by the very low temperature in the case so that air coming downwardly into it will be at a lower temperature at the lower end than comes in at 75 the upper end, so that the air will start to descend

within the condenser as a local confined convection current, and at the same time owing to the extremely low temperature of the wall of the condenser any moisture carried by the descending air will be deposited as either frost or moisture 5 on the walls of the tube 28. The dehydrated air with its initial fall and establishment of a descending current will pass laterally out of the condenser and through bore 32 into space 13 between the panes 12 and 14. Owing to the slight 10 pressure behind it, and also to the fact that a slight suction is being exerted upon it for the purpose (as will be pointed out) the air moves in space 13 longitudinally and upwardly, sweeping 15 between the glasses, until it passes through bore 35 into the upper part of channel or space 15, in which it sweeps downwardly and longitudinally and through low bore 36, pursuant to which it sweeps longitudinally and upwardly from the lower part of space 17, to the exhaust bore 20 or aperture 34, into the pipe 33, in which it runs initially longitudinally of the space 17, and from which it runs rearwardly into the top of the cylinder 28, and the cycle is complete. The series 25 circulation thus established is definitely facilitated and augmented by the fact that the front pane is warm enough to impart energy to the circulation, and thus to create suction on the circuitous channel just described. To this end the conduit 33 may be insulated until after it empties 30 into the condenser 28, to help maintain a circulation.

In this latter connection, it is contemplated 35 that an auxiliary source of heat may be provided, preferably within the front space 17, such as an electric resistance unit or small wire or the like lying in the lower part of the space, or by providing the heat circulating pipe 38 lying in the bottom of the space 17, and having a substantially vertical portion disposed in close proximity to 40 the hot portion of the condenser of the freezing unit, so as to establish a closed confined convection current within the pipe 38. Obviously the warmed air rises in the pipe 38, gives up its 45 heated energy in the space 17, and descends out of the far end of the space 17 as a descending cooled air stream, to maintain the circulation. This heat energy imparted to the air in the space 17 causes an acceleration of the upward flow and its exhaust into the upper end of the 50 condenser tube 28.

In order to minimize the "break-down" of the sealing insulation about the edges of the panes it is important to maintain the circulating dehydrated air stream passing through the window 55 at a pressure which does not depart from atmospheric by any but the smallest quantities. This may be easily and cheaply accomplished by providing a minute pin hole 40 at the bend of the pipe 33 as it enters the tube 28. If desired a 60 delicate valve mechanism can be associated therewith so as to respond to inner and outer differential pressures of a magnitude less than that which will break down the insulating seal of the panes. However, in general the minute aperture 40 will possess such frictional coefficient on air passing through it, that it is easier for the 65 syphon action (so to speak) of the incoming warm air entering the condenser tube, while the descending cooled air stream exerts suction to pull the warm air through and down, than it will be for the suction or partial vacuum to be released or satisfied with the air entering the pin hole 40. Particularly is this true when the acceleration of the upward flow in the front space 70 75

through the gentle warming of the air in that space is considered.

It will be recognized that there are periodic defrosting stages in the cycle of operation of the unit of the show case, and as the temperature in the case is allowed to rise to melt the frost on coils 27, a similar result will be derived from the warmed condenser tube 28, so that the frost on its inner surface will be melted and will run down and be collected in the cup 30 at the bottom of the tube. As the temperature is again lowered, any moisture that might have been picked up by the circulating window stream is carried through until it is re-deposited internally of the tube 28. It will be understood that the dew point of the air leaving the bottom of tube 28 is always lower than that attaching to any of the panes of the window, so that no condensation on the inner surfaces of the panes can occur.

The cheapness, efficiency and minimized service requirements devolving upon the use of the invention will be evident, as will the fact that many changes can be made in the invention without detracting from its scope and without avoiding the terms of the appended claims. Obviously the circulation can pass through suitable apertures in the frame in place of through bores formed in the glass.

I claim as my invention:

1. In refrigerator windows, a plurality of spaced panes defining a plurality of spaces between the panes, a closed metallic condensing tube having vertically spaced ends, conduit means extending from the lower end of the tube to communicate with the adjacent space between panes, conduit means extending from the upper end of the tube and communicating with another space between panes, and means establishing communication between the said two mentioned spaces between panes.

2. In refrigerator windows, a plurality of spaced panes defining a plurality of spaces between the panes, a closed metallic condensing tube having vertically spaced ends, conduit means extending from the lower end of the tube to communicate with the adjacent space between panes, conduit means extending from the upper end of the tube and communicating with another space between panes, and means establishing communication between the said two mentioned spaces between panes, said last mentioned means comprising a bore through a pane.

3. In refrigerator windows, a plurality of spaced panes defining a plurality of spaces between the panes, a closed metallic condensing tube having vertically spaced ends, conduit means extending from the lower end of the tube to communicate with the adjacent space between panes, conduit means extending from the upper end of the tube and communicating with another space between panes, and means establishing communication between the said two mentioned spaces between panes, and means for introducing heat energy into the space between the panes connected to the conduit leading to the top of said tube.

4. In refrigerator windows, a plurality of spaced panes defining an air space, conduits communicating respectively with the upper and lower ends of said space, a metallic condenser substantially sealed to said conduits to complete a closed circulatory path, and means for chilling the condenser to dehydrate the circulating air, and a minute aperture communicating with said condenser to permit relative expansion and contraction of the circulating air without stopping the circulation.

5. In refrigerator windows, a plurality of spaced panes establishing a plurality of communicating air spaces, a condensing tube comprising a thin wall metallic tube the ends of which are at different levels, means establishing communication between the tube and the respective spaces adjacent to and remote from the tube, said means having an inlet and an outlet in staggered relation, the lower end of the tube comprising a removable cap, and means for leading air into and from the respective levels of the tube through a window space between panes, and said cap containing dehydrating material.

6. In refrigerators, means defining a refrigerator compartment and including a window, means including a condenser for lowering the temperature in the compartment, said window comprising a plurality of spaced panes, means for circulating air through the space between the panes, a pipe disposed in the said space between the panes and leading to a point in such proximity to said condenser as to conduct heat therefrom into said space to accelerate the air flow through said space and to warm the adjacent panes.

7. In refrigerators, means defining a refrigerator compartment and including a window, means including a condenser for lowering the temperature in the compartment, said window comprising a plurality of spaced panes, means for circulating air through the space between the panes, a pipe disposed in the said space between the panes and leading to a point in such proximity to said condenser as to conduct heat therefrom into said space to accelerate the air flow through said space and to warm the adjacent panes, and a metallic condensing tube disposed in said compartment and maintained at low temperature, said means for conducting the air comprising connections between said tube and the space between the panes.

8. In refrigerators, means defining a refrigerator compartment and including a window, means including a condenser for lowering the temperature in the compartment, said window comprising a plurality of spaced panes, means for circulating air through the space between the panes, a pipe disposed in the said space between the panes and leading to a point in such proximity to said condenser as to conduct heat therefrom into said space to accelerate the air flow through said space and to warm the adjacent panes, a metallic condensing tube disposed in said compartment and maintained at low temperature, said means for conducting the air comprising connections between said tube and the space between the panes, and auxiliary means permitting expansion and contraction of the pressure of the circulating air stream without affecting the circulation.

9. In refrigerators, a plurality of spaced panes defining a plurality of spaces between panes, a closed conduit in such refrigerator, and means conducting air from said conduit in series through the spaces to return to the conduit.

10. In refrigerators, means defining a refrigerating compartment and a window, a refrigerating unit in said compartment, said unit being in a cooling system having a condenser outside of said compartment, said window comprising a plurality of spaced panes forming a plurality of air spaces and having staggered bores to provide a path for air to flow through said spaces in series, a condensing tube forming a portion of said air series path and exposed within said compartment for dehydrating purposes, and means extracting heat from said condenser to warm the air in the

pane spaces and promote circulation therethrough.

11. In refrigerators, means defining a refrigerator compartment and a window, a refrigerating unit in said compartment, said unit being in a cooling system having a condenser outside of said compartment, said window comprising a plurality of spaced panes forming a plurality of air spaces, each pane, other than the outer pane,
10 having a bore therethrough to form a communication between adjacent spaces, said bores being so located that air travels laterally and longitudinally of each space and in series through said spaces, a condensing tube forming a portion of
15 said air series path and exposed within said compartment for dehydrating purposes, and means extracting heat from said condenser to warm the

air in one of said pane spaces to promote circulation of air therethrough.

12. In refrigerators, means defining a refrigerator compartment and a window, a refrigerating unit in said compartment, said window comprising a plurality of spaced panes forming a plurality of air spaces, each pane, other than the outer pane, having a bore therethrough to form a communication between adjacent spaces, said bores being so located that air travels laterally and longitudinally of each space and in series through said spaces, and a condensing tube in said compartment having connections communicating respectively with the inner and outer window spaces.

ROBERT M. ROBINSON.
